UNITED STATES PATENT OFFICE.

ROBERT J. JOHNSTON, OF KANSAS CITY, MISSOURI.

WALL-BOARD STRUCTURE.

Application filed September 6, 1921. Serial No. 493,743.

To all whom it may concern:

Be it known that I, ROBERT J. JOHNSTON, a citizen of the United States, residing at Kansas City, in the county of Jackson and 5 State of Missouri, have invented a certain new and useful Improvement in Wall-Board Structures, of which the following is a complete specification.

The present invention relates to wall board, such as is used for providing an interior wall facing, and aims to provide an improved wall board construction made up of wall board sections adapted to be so matched together as to present a practically 10 unbroken and continuous wall surface, the joints or seams between the sections of the wall board being maintained substantially air tight and proof against the passage of insects or vermin.

20 To this end, I have devised a wall board structure made up in sections, each of which is formed with lips extending longitudinally along its opposite side edges, and continuous with one face of the section, and arrange 25 these sections in alternately reversed relation so that the side lips are matched together in lapping relation, resulting in a wall board of perfectly even and uniform cross-section throughout and adapted to be 30 maintained in this condition by securing means applied to the seams or joints formed by the overlapping lips of the adjoining wall board sections.

With the foregoing general objects in 35 view, the invention will now be described by reference to the accompanying drawing illustrating one form of construction which I have devised for embodying the proposed improvements, after which the novel features therein will be particularly set forth and claimed.

In the drawing—

40 Figure 1 is a perspective view illustrating a wall board panel or a section constructed in accordance with the present invention;

45 Figure 2 is an elevation showing a portion of a wall board structure having a plurality of the improved wall board panels or sections matched together as proposed by 50 the improvements; and

Figure 3 is a horizontal sectional view, of the wall board structure.

55 Referring now to the drawing in detail, this illustrates the invention as embodied in any suitable wall board material, such as is commonly made up in sheets, sections or

panels, of strawboard, wood pulp, or wood fibre and plaster, these materials being treated by any preferred mode of molding operation for producing wall board sheets 60 or sections of the proper size and dimensions. In the present case, the invention comprises as one unit, a wall board section 6 of any required length and width, and so formed or molded as to produce along the 65 opposite side edges of the section or panel suitable lips or flanges 7 which are continuous with one of the faces of the panel, as clearly represented in Figures 1, 3 and 5. By means of this construction, it will be 70 seen that when a plurality of the sections or panels 6 are to be assembled in forming the interior facing of a wall, the lips or flanges 7 are adapted to be matched together in lapping relation, by the simple 75 operation of alternately reversing the consecutive sections or panels 6, as shown in Figures 2 and 3. This results in neat and close fitting joints or seams along the overlapping lips or flanges 7, with no extra 80 thickness of the material at these points, and no additional securing means being required, aside from the usual tacks or nails 8, used for tacking the wall board in position. In practice, the width of the wall 85 board section 6 may be so chosen as to span the distance between the joists or studs 9, so that the overlapping lips or flanges of adjoining sections will come over the several 90 joists 9, and the nails 8 driven alongside 95 the overlapping lips and thereby secured to the joists.

It will thus be seen that I have devised a practical and at the same time extremely simple wall board construction for fulfilling the objects of the invention. The sections or panels 6 are all made in duplicate form, so that all that is required in the assembling of the sections is the reversal of every other section in order to match up the 100 lips 7 in the manner illustrated. While this results in the width of every other panel of the wall board construction being just slightly narrower or wider than the next adjacent panels, due to the lapping of the 105 lips 7 and the reversal of consecutive sections 6, the lips 7 may be made so narrow that this difference in the widths of the panels may be made so small as to be unnoticeable. The improved construction provides a solid, even, uniform, and unbroken 110 wall surface, which may also be made prac-

tically air tight, and the lapping character of the joints or seams between the sections is such that these seams or joints can be so tightly sealed as to exclude insects or 5 vermin of every nature.

What I claim is:

1. A wall board structure comprising, in combination with wall studs a plurality of wall board sections, each having longitudinal lips along the opposite sides thereof and continuous with one of its faces, said sections being alternately reversed with the adjoining sections having their lips in lapping relation, and the combined thickness of each pair of lapped lips equaling 10 the thickness of the main body portions of 15 said sections and means for securing said

sections to said studs with said lips in lapped relation.

2. A wall board structure comprising, in combination with wall studs, a plurality of wall board sections, each having longitudinal lips along the opposite sides thereof and continuous with one of its faces, said sections being alternately reversed with the 20 adjoining sections having their lips in lapping relation along said studs, and nails extending through each of said sections adjacent each of its lip portions and into said 25 studs for securing said sections thereto with 30 the lips in lapped relation.

In witness whereof I hereunto affix my signature.

ROBERT J. JOHNSTON.
